UNITED STATES PATENT OFFICE.

GEORGE H. DAWSON, OF BOSTON, MASSACHUSETTS, ASSIGNEE TO LIBRARY BUREAU,
OF CAMBRIDGE, MASSACHUSETTS, A CORPORATION OF NEW JERSEY.

INDEX TAB.

Application filed February 28, 1924. Serial No. 695,244.

To all whom it may concern:

Be it known that I, GEORGE H. DAWSON, a citizen of the United States of America, and resident of Boston, in the county of 5 Suffolk and State of Massachusetts, have invented new and useful Improvements in Index Tabs, of which the following is a specification.

This invention relates to indexes and particularly to the construction of the tab of 10 a heavy stiff card such as is commonly employed as a guide or divider to separate into groups the cards, folders or other index matter constituting a filing system of the 15 so-called vertical type.

The principal object of the invention is to provide a novel form of metal tab having an unusually large sight opening or window for displaying the label or index 20 slip but yet sufficiently stiff and strong to serve as a handle for turning over the index material; to provide a tab capable of use in connection with either a permanent or removable label, and in the latter case effectively to prevent accidental loss or removal 25 of the label; and to provide a tab having smooth edges agreeable to the touch of the user; which is reinforced to make it relatively stiffer than the sheet material from 30 which it is stamped; and whose edges so snugly engage the surface of the card that it is impossible for papers to enter and catch between them.

The accompanying drawings illustrate a 35 preferred embodiment of the invention.

Fig. 1 is a fragmentary front elevation of the upper part of an index card having the improved tab applied thereto;

Fig. 2 is an end elevation, to larger scale, 40 of the parts shown in Fig. 1;

Fig. 3 is a vertical section to large scale on the line 3—3 of Fig. 1;

Fig. 4 is a horizontal section on the line 4—4 of Fig. 1 to larger scale; and

Fig. 5 is a view similar to Fig. 3, but 45 illustrating the application of the tab to a card having a permanent label.

The card body 1 is made of cardboard, 50 fibreboard, or other suitable stiff and heavy sheet material. The tab forming the immediate subject matter of the invention consists of a piece of resilient sheet material such for example as steel doubled or folded at 2 to provide substantially rectangular

front and rear flaps or leaves 3 and 4, respectively.

The flaps are of shallow, dished formation with slightly rolled or incurved margins forming smoothly rounded or convex borders or flanges 5 and 6, respectively, whose 60 edges turn inwardly, thus imparting strength and a finished appearance to the tab.

Sight openings or windows 7 and 8 are preferably provided in both the front and 65 rear flaps adjacent to the fold line 2, although if desired the window 8 in the rear flap may be omitted.

When intended for use with a removable label as illustrated in Figs. 1 to 4 inclusive, the tab straddles over the plain upper margin 9 of the card and the front and rear flaps are connected to each other and to the card by fasteners 10 which extend through the body of the card. The patent to Hunter 905,319, December 1, 1908, discloses fastening means suitable for the purpose consisting of integral tubular rivets struck up from the front flap and extending through the thickness of the card 80 and through openings in the rear flap, the ends of the rivets turning over against the rear face of the latter flap. Other forms of connection may be employed if desired.

In the riveting operation the central portions of the dished flaps are sprung inwardly toward the card thus causing the edges of their flanged margins to bite into the surface of the card forming a closed and tight joint.

In placing the tab over the edge of the card, its closed upper end is spaced from the card a proper distance to provide a label-receiving pocket 11. When the tab is riveted to the card, those portions or lips 5^a and 6^a of the inturned margins of the flaps which are above the upper edge of the card spring toward each other forming partial closures for the ends of the label-holding pocket.

Any suitable label may be placed in the pocket by sliding it endwise between the lips 5^a and 6^a. A label suitable for the purpose is disclosed in the patent to Gale, 1,370,424, March 1, 1921. This label consists of a slip of paper 12 bearing the desired indicia and protected by a transparent sheath 13 of celluloid or the like. To in-

sert such a label in the pocket its parts are pinched together to permit them to pass between the lips 5^a and 6^a and when the entire label has been positioned within the 5 pocket its parts spring away from each other sufficiently to prevent its accidental escape from the pocket.

In Fig. 5 the tab is shown as applied to a card 1^a having an upstanding ear 14 constituting a permanent label. The desired indicia are applied directly to the front face (and also, if desired, to the rear face) of the ear 14, and a transparent sheath 15 is slipped over the ear to protect its surfaces 10 when they are exposed at the windows in the tab. The tab is then straddled over the ear, the upper edge of the latter being disposed closely adjacent to the fold line of the tab so that the ear itself determines 15 the depth of the label-receiving pocket and the front and rear leaves 3^a and 4^a of the tab are secured to the card in the manner above described.

The tab is preferably slightly wider than 25 the ear 14 and when in position its inturned edges substantially meet along the lateral margins of the ear, thus protecting the latter and providing a smooth finish for the projecting portion of the tab.

30 The tab above described has several advantages, among them its one-piece construction, which permits it to be manufactured cheaply and to be applied to the cards without difficulty or loss of time. It is 35 shaped to provide a wide bearing on the card so that when employed as a handle the card is not easily cracked or broken out. The incurved margins of the opposing flaps of the tab constitute strengthening ribs or 40 flanges which greatly stiffen the tab, particularly the projecting portion thereof, thus optionally permitting the employment of lighter weight and consequently cheaper material or the enlargement of the sight opening 45 or window to an extent greater than usually permissible, without detracting from its desired rigidity and durability. These in-turned edges or flanges also tend to bite firmly into the surface of the card, thus assisting the rivets or other securing means 50 in holding the tab in position, at the same time forming so tight a joint with the card that thin paper can not slip between the card and tab to be caught and possibly torn 55 or misplaced. These inturned margins also constitute partial end closures for the ends of the label pockets as above pointed out and at the same time provide a smooth rounded edge for the projecting portion of 60 the tab which is frequently employed as a handle for turning the cards.

Obviously sheet material other than steel may be employed in making the tab. For example, stiff sheet celluloid might be employed, and if transparent, no windows or

sight openings would be necessary, while many of the advantages of the improved construction, such for example as stiffness, durability, and the formation of a close joint with the card would be retained. 70

I claim:

1. An index card comprising a tab of resilient sheet material having an attaching flap provided with marginal flanges, and means engaging the central portion of the flap for permanently uniting it to the card, said latter means acting to spring the central portion of the flap inwardly whereby to draw the flanges thereof into close engagement with the surface of the card. 80

2. An index card comprising a tab of resilient sheet metal having an attaching flap of shallow dished formation providing an inturned marginal flange, and rivets permanently securing the flap to the card, said rivets engaging the flap intermediate its edges and springing its central part toward the card whereby resiliently to hold the flange in biting engagement with the surface of the card. 90

3. An index card having a tab comprising front and rear flaps of shallow dished formation providing inwardly bent marginal portions, and means permanently securing the tab to the card with the inwardly directed edges of its flaps engaging the front and rear surfaces respectively of the card. 100

4. An index card having a tab comprising a piece of sheet material doubled to form front and rear flaps, the flaps having window apertures, and having their marginal edges turned inwardly, said tab straddling the edges of the card, and means permanently securing the flaps to the card with the in-turned edges of the flaps engaging the opposite faces respectively of the card. 105

5. An index card having a tab comprising a piece of sheet metal doubled to form front and rear flaps, said tab straddling the edge of the card and having its fold spaced from the edge of the card to form a label-receiving pocket, and means permanently securing the flaps to the card, marginal portions of the flaps being turned in to form partial closures for the ends of the label-receiving pocket. 110

6. An index card having a tab comprising a piece of sheet metal doubled to provide front and rear flaps, said flaps having window apertures at points adjacent to the fold line and the tab straddling the edge of the card with its fold line spaced from the latter to form a label-receiving pocket, means permanently securing the flaps to the card, and an inturned marginal flange extending from the fold line around the entire border flap, portions of said flanges constituting partial closures for the ends of the label-receiving pocket and other portions engaging and biting into the surface of the card. 120

7. An index card having a sheet metal tab comprising integrally united front and rear flaps provided with window apertures, the flaps being disposed upon opposite sides of the card and permanently secured thereto with their apertured portions projecting beyond the edge of the card, and a stiffening rib or flange extending along the projecting portion of each flap at either side of the window aperture therein.

8. An index card having a tab comprising a piece of sheet material folded to form front and rear flaps, said flaps having window openings therein, the tab straddling the

edge of the card with its flap disposed upon opposite sides thereof respectively and permanently secured thereto with the fold line of the tab spaced from the edge of the card proper to form a pocket, an ear projecting integrally from said edge of the card into the pocket and constituting a permanent label, and a lip extending along the projecting portion of each flap adjacent to each lateral margin thereof, said lips partially closing the sides of the pocket.

Signed by me at Boston, Massachusetts, this sixth day of February, 1924.

GEORGE H. DAWSON.

7. An index card having a sheet metal tab comprising integrally united front and rear flaps provided with window apertures, the flaps being disposed upon opposite sides of the card and permanently secured thereto with their apertured portions projecting beyond the edge of the card, and a stiffening rib or flange extending along the projecting portion of each flap at either side of the window aperture therein.
8. An index card having a tab comprising a piece of sheet material folded to form front and rear flaps, said flaps having window openings therein, the tab straddling the edge of the card with its flap disposed upon opposite sides thereof respectively and permanently secured thereto with the fold line of the tab spaced from the edge of the card proper to form a pocket, an ear projecting integrally from said edge of the card into the pocket and constituting a permanent label, and a lip extending along the projecting portion of each flap adjacent to each lateral margin thereof, said lips partially closing the sides of the pocket.

Signed by me at Boston, Massachusetts, this sixth day of February, 1924.

GEORGE H. DAWSON.

Certificate of Correction.

It is hereby certified that in Letters Patent No. 1,544,818, granted July 7, 1925, upon the application of George H. Dawson, of Boston, Massachusetts, for an improvement in "Index Tabs," errors appear in the printed specification requiring correction as follows: Page 2, line 103, claim 4, for the word "edges" read *edge*; same page, line 126, claim 6, after the word "border" insert the words *of each*; and that the said Letters Patent should be read with these corrections therein that the same may conform to the record of the case in the Patent Office.

Signed and sealed this 18th day of August, A. D. 1925.
